UNITED STATES PATENT OFFICE.

LOUIS P. BABEU, OF GRAVELBOURG, SASKATCHEWAN, CANADA.

SNAP AND BUCKLE.

Application filed March 6, 1922. Serial No. 541,505.

To all whom it may concern:

Be it known that I, LOUIS P. BABEU, a citizen of the United States, residing at Gravelbourg, in the county of Saskatchewan and Dominion of Canada, have invented certain new and useful Improvements in Snaps and Buckles, of which the following is a specification.

This invention relates to improvements in 10 a combined buckle and snap hook and has for its object to provide such a device especially adapted for use in connection with harness.

Another object of the invention is to provide 15 a harness buckle so arranged that the strap held by the buckle will control a snap hook connected to said buckle.

A still further object of the invention is to provide a buckle having a snap hook pivotally connected thereto and so arranged 20 that the strap held by said buckle will control the action of said hook.

With the above and other objects in view I have invented the device illustrated in 25 the accompanying drawings, in which—

Figure 1 is a side elevational view of my snap hook and buckle shown in operative position;

Figure 2 is a similar view, the snap being 30 shown in inoperative position;

Figure 3 is a top plan view of Figure 1;

Figure 4 is a section on line 4—4 of Figure 3; and

Figure 5 is a front end elevational view 35 of the device.

Like reference characters indicate like parts throughout the following specification and in the several views in the drawings in which, 1 indicates a combined snap hook 40 and buckle which consists of a buckle 2, having a projecting end 3 to which the snap hook 4 is pivotally connected by means of a rivet pin 5, which projects through the spaced apart similarly formed side walls 6 and 7 of the snap hook, and the enlargement 45 8 of said member 3 which seats between the lower ends 9 and 10 of said members 6 and 7 and which also forms a spacer for said ends 9 and 10. The members 6 and 7 are provided with rearwardly projecting arms 11 and 12 having opposing apertures 13 to receive the rivet pin 14 by means of which the rear portion 15 of the jaw member 16 is pivotally connected to said arms 11 and 12. The forward ends of the members 6 and 55 7 are upwardly inclined and terminate in

hooks 17 and 18 held spaced apart by the spacer rivet 19 and the forward end of the member 16 terminates in a hook 20 which 60 slidably operates between the members 17 and 18, said latter hook being arranged in opposing position relative to the members 17 and 18. The buckle 2 is provided with a pair of spaced apart longitudinal slots 21 and 22 separated by a tine 23 and adapted 65 to receive the end 24 of the strap 25, said strap being provided with a longitudinally arranged slot 26 near its terminal 27 the purpose of said slot 26 being to receive the hook 28 formed on the rear terminal 29 of 70 the member 16. The strap terminal 27, acting upon the member 28, holds the jaw hook 20 between the similarly formed members 17 and 18 to engage the ring 30 on the end 75 of the strap 31 in which position said members will remain both through the action of said strap terminal 27 and through the curvature of said hook jaws 17, 18 and 20. A stud 32 is provided on the pin 23 against which the member 28 is adapted to abut 80 when the terminal 27 of said strap is drawn a sufficient distance down towards said stud. This arrangement prevents any possibility of accidental opening or separation of the 85 jaw member 20 from the members 17 and 18, as indicated in dotted lines in Figure 1. However, upon sufficient finger pressure upon the portion 33 of the member 16, the forward part of said member may be pressed down out of engagement with the jaw hooks 90 17 and 18, as indicated in dotted position, Figure 2.

Having described my invention that which I claim as new and desire to procure by Letters Patent is:

1. A device of the character described including a buckle having a bracket extension and a snap hook pivoted to said extension, said snap hook being strap controlled, said strap being held by said buckle, said snap hook consisting of pivotally connected jaw members;

2. A device of the character described including a buckle having a bracket extension and a snap hook pivoted to said extension, 105 said snap hook being strap controlled, said strap being held by said buckle, said snap hook consisting of pivotally connected jaw members, one of said members having a terminal connected with said strap;

3. A device of the character described including a buckle having a bracket extension 110

and a snap hook pivoted to said extension, said snap hook being strap controlled, said strap being held by said buckle, said snap hook consisting of pivotally connected jaw members, one of said members having a terminal connected with said strap, said strap having a slot to receive said terminal;

4. A device of the character described including a buckle having a bracket extension, 10 and a snap hook pivoted to said extension, said snap hook being strap controlled, said strap being held by said buckle, said snap hook consisting of pivotally connected jaw members, one of said members having a terminal connected with said strap, said strap having a slot to receive said terminal, said terminal being in the form of a hook;

5. A device of the character described including a buckle having a bracket extension, 20 and a snap hook pivoted to said extension, said snap hook being formed of a pair of similarly formed spaced apart members and a hook member pivotally mounted between said members, said members having hook terminals adapted to co-act with the hook terminal of said other member;

25 6. A device of the character described in-

cluding a buckle having a bracket extension, said snap hook pivoted to said extension, 30 said snap hook being formed of a pair of similarly formed spaced apart members and a hook member pivotally mounted between said members, said members having hook terminals adapted to co-act with the hook terminal of said other member, means whereby 35 a strap controls said hook member;

7. A device of the character described including a buckle having a bracket extension, said snap hook being formed of a pair of 40 similarly formed spaced apart members and a hook member pivotally mounted between said members, said members having hook terminals adapted to co-act with the hook terminal of said other member, means whereby 45 a strap controls said hook member, said buckle having a stop adapted to limit the action of said snap hook.

In testimony whereof I affix my signature in the presence of two witnesses.

LOUIS P. BABEUF.
